(57) **CLAIM**

The ornamental design for the end cap for an insect trap, as shown.

DESCRIPTION

FIG. 1 is an upper-front view of an end cap for an insect trap in accordance with the present invention;

FIG. 2 is a lower-front view of the end cap for an insect trap shown in FIG. 1;

FIG. 3 is a top plan view of the end cap for an insect trap shown in FIG. 1;

FIG. 4 is a bottom plan view of the end cap for an insect trap shown in FIG. 1;

FIG. 5 is a front view of the end cap for an insect trap shown in FIG. 1, which due to symmetry is the same as a back view;

FIG. 6 is a left side view of the end cap for an insect trap shown in FIG. 1, which due to symmetry is the same as a right side view;

FIG. 7 is a sectional view of the end cap for an insect trap shown in FIG. 1, through section 7-7 indicated in FIG. 3; and,

FIG. 8 is a sectional view of the end cap for an insect trap shown in FIG. 1, through section 8-8 indicated in FIG. 3.
